LUMINESCENT LAMP

Humboldt W. Leverenz, South Orange, N. J., assignor to Radio Corporation of America, a corporation of Delaware

Application February 28, 1941, Serial No. 381,032

11 Claims. (Cl. 176—122)

My invention relates to improvements in luminescent lamps and particularly to lamps and lamp auxiliaries which in combination produce light of high intrinsic brilliance.

Luminescent lamps are known wherein a coating of finely divided phosphor or luminescent material is provided on the interior surface of an envelope which material upon excitation by corpuscular or radiant energy becomes luminescent. The intrinsic brilliance of such devices is very low and they are not adapted for the production of light of high intrinsic brilliance. Further disadvantages of such lamps resides in the fact that the luminescent material which is in a finely divided powdered form absorbs as well as diffuses an appreciable proportion of the emitted light.

In my copending application Serial No. 348,790, filed July 31, 1940, and now Patent No. 2,298,947 issued Oct. 13, 1942, I described a luminescent lamp of exceptionally high intrinsic brilliance wherein the luminescent material was composed of solid elongated phosphor bodies. I likewise described in my prior application a lamp utilizing the cumulative effect of a plurality of luminescent solids comprising transparent phosphor members to provide an extended excitation volume in a transparent luminescent solid.

Objects of my present invention include providing luminescent lamps of exceptionally high intrinsic brilliance; lamps of high intrinsic brilliance having a wide range of colors or band spectrum emissions within the ultra-violet and infra-red portions of the spectrum; lamps of exceptionally high intrinsic brilliance of the electron discharge type capable of utilizing the excitation energy more efficiently. Another object of my invention is to provide a lamp of the type described which may be modulated with respect to the intensity of the developed light of high intrinsic brilliance. A further object is to provide a highly efficient lamp of smaller dimensions than heretofore practicable. Still further objects of my invention are to provide auxiliary means to control the paths of corpuscular excitation energy in a lamp excited by corpuscular radiation and lamps capable of propagating light with highly directional characteristics with high luminous efficiency and relatively low excitation potentials.

In accordance with my invention I provide a luminescent lamp excitable by corpuscular energy such as an electron discharge wherein the material which becomes excited under the incident energy comprises elongated transparent phosphor bodies in combination with means to subject the

bodies to corpuscular radiation incident thereon over controlled paths intercepting the bodies at angles other than normal to the surface of the bodies. More particularly in accordance with my invention I provide means for use with the devices of the type described to direct luminescence exciting electrons upon the elongated transparent phosphor bodies along paths intercepting the bodies at angles other than normal to the surface of the bodies. Still further means are provided for developing light of high intrinsic brilliance and for varying or modulating the intensity of the light developed. These and other objects, features and advantages of my invention will become apparent to those skilled in the art when considered in view of the following description and the accompanying drawings in which:

Figure 1 is a longitudinal cross sectional view 20 and schematic circuit of one form of luminescent lamp and auxiliary apparatus made in accordance with my invention;

Figure 2 is a cross section of the device shown in Figure 1 taken along the lines 2—2; and

Figures 3 and 4 are views similar to Figures 1 and 2 showing a further modification of my invention.

The lamp shown in Figures 1 and 2 is particularly adapted for producing high intensity light beams such as for search-light use or other applications wherein a high concentration of light from a source of high intrinsic brilliance is desired. The lamp shown is of the type described in my above-mentioned copending application the exciting energy being corpuscular excitations such as high velocity electrons. The lamp of Figure 1 comprises an elongated evacuated envelope 1 closed at one end of the envelope by a lens portion 2. The envelope 1 with the exception of the lens portion 2 is preferably provided on its exterior surface with a light opaque reflecting coating 3 which prevents liberation of light over the length and at one end of the envelope, directing light through the portion 2 in the form of a beam of high illuminating value.

In accordance with my invention I provide a plurality of transparent solid phosphor bodies comprising thin plate-like phosphor sheets 10 which are preferably of rectangular shape supported within the envelope 1 and separated one from the other by predetermined distances depending upon the operating parameters herein-after set forth. It will be noted that I have shown two pairs of three sheets 10 designated 10a, 10b and 10c. I provide intermediate the

sheets 10a a plurality of cathodes 11 which may be of the directly or indirectly heated type coated on their exterior surfaces with barium and strontium oxides or other electron emitting material. While I have shown a plurality of cathodes 11, it will be obvious that a single cathode of rectangular shape may be used. Between the sheets 10a and the cathodes 11 I provide electron permeable anodes 12a to direct the electrons from the cathodes 11 and project them toward and upon the phosphor sheets 10a.

In accordance with a further teaching of my invention the sheets 10a may be of insufficient thickness to absorb all the energy of the electrons impinging thereon. Thus the electrons deliver the greater portion of their energy to the phosphor sheets 10a but retain sufficient energy to pass through these sheets into the space on the opposite side from the cathodes 11. The electrons passing through the sheets 10a are re-accelerated by the anodes 12b and impinge on the plates 10b which are likewise of insufficient thickness to absorb all of the electron energy, whereupon the electrons are again accelerated by the anodes 12c and impinged on the phosphor sheets 10c which are preferably of sufficient thickness to absorb all the electron energy. The sheets 10c may be of the same thickness as the sheets 10a and 10b provided a lower potential is applied to the anodes 12c than to the anodes 12a and 12b. While I have shown only three phosphor sheets and their associated anode structures on opposite sides of the cathodes 11, it will be obvious that the systems of phosphor sheets and anodes may be repeated to obtain even higher total brilliance. Additional cathodes or thermionic emitters may likewise be provided between the sheets 10a and 10b and between 10b and 10c.

The ratio of maximum dimension, such as the length of the sheets 10, to the minimum dimension, such as their thickness, should preferably be no less than 5 to 1, although a ratio of 3 to 1 may be sufficient such as where a plurality of sheets placed end to end are used. With these and greater ratios of length to minimum dimension the length is sufficient to exhibit total internal reflection of light predominantly along and within the length of the phosphor sheets. Likewise the sheets 10 preferably consist of a single crystal of the phosphor. By single crystal is meant a crystal of both perfect and imperfect symmetry, and therefore this term includes a twin crystal, especially twinning of the interpenetration type which produces a minimum of optical inhomogeneity.

The potentials applied to the anodes 12 may be of the order of 10,000 to 300,000 volts positive with respect to the cathode potential or may be of this order alternating potential depending upon the thickness of the phosphor sheets 10. However, the potentials applied to the various anodes may be different, with the associated phosphor sheet thickness being chosen insufficient to absorb all of the electron energy for the desired anode operating potential.

I have found in accordance with a further teaching of my invention that the efficiency of solid phosphor bodies may be increased by increasing the secondary electron emission occurring at the surface of or within the solid phosphor bodies. Therefore, in accordance with this teaching of my invention I provide means in combination with the structures I have described to direct the electrons such as from the cathodes 11 upon the phosphor sheets 10a and further up-

on the sheets 10b and 10c at acute angles thereby increasing the secondary electron emission of the phosphor sheets.

Referring again to Figures 1 and 2 I provide means to generate a magnetic field extending longitudinally over the length of the phosphor sheets, such as a longitudinal magnetic field generating coil 15 which incloses substantially the entire length of the envelope 1. The use of such a coil is obviously impractical and unnecessary in combination with conventional fluorescent lamps excited principally by ultra-violet light generated in a vapor discharge and wherein the generated light is propagated in substantially all directions over the length of the lamps. However, in a lamp made in accordance with my invention the light propagation is through the end of the envelope 1 such as though the transparent portion 2 and the exciting energy is electron irradiation which may be controlled by my magnetic means. As indicated above, the spacings between the adjacent sheets 10, such as between the sheets 10a and 10b and between 10b and 10c, are so chosen that the electrons liberated from the cathodes 11 and impinging upon the plates 10a, or the electrons passing through the sheets 10a and 10b follow curved paths incident upon the phosphor sheets 10a or succeeding sheets at an acute angle so that the impinging electrons liberate secondary electrons greatly in excess of the number of impinging electrons. The impinged surfaces of the phosphor sheets thereby acquire high positive potentials due to the loss from the surfaces of secondary electrons and the surfaces are thus driven to a potential substantially equivalent to that of the adjacent anode. On the other hand, if the secondary electron emission is less than unity, the surfaces of the sheets 10 acquire limiting potentials which decelerate the approaching electrons thereby reducing the efficiency of the device.

The distance D, through which an electron moves toward an electrode in a crossed magnetic and electrostatic field may be represented by the equation:

$$45 \quad D = \frac{E}{H^2 e} \left(1 - \cos \frac{H^2 e t}{m} \right) \quad (1)$$

where E is the electrostatic potential gradient in electro-magnetic units per centimeter, H is the magnetic field strength in gauss, e/m is the ratio of charge to mass of the electron and t is the time in seconds.

Equation 1 may be simplified assuming the spacing between the cathode and phosphor body 55 as equal to D and becomes:

$$50 \quad D = \frac{2E}{H^2 e} \quad (2)$$

60 which in practical units, where V is expressed in volts impressed between the cathode and phosphor body, becomes:

$$65 \quad D = \left(\frac{11.3V}{H^2} \right)^{\frac{1}{2}} \quad (3)$$

Obviously for a spacing between the cathodes 11 and the sheets 10a equal to D in the above equation the electrons from the cathodes 11 would not impinge on the sheets 10a. The actual separation between the cathodes and the adjacent plates should, therefore, be less than the value D given above in terms of the potential differences and the magnetic field.

The increase in secondary electron emission 75 occasioned by the use of the magnetic field re-

sults in a higher energy conversion efficiency thereby developing more light for given energy input levels. Thus, the probability of an electron impinging on a phosphor surface is increased, especially in devices utilizing phosphor bodies in the form of single crystal rods as disclosed in my above-mentioned application. As a result, the size of the device may be decreased while still retaining the advantages of high levels of illumination and even greater efficiencies than devices used heretofore.

The light output of the device shown in Figures 1 and 2, may be controlled or modulated by the use of a grid structure (not shown) surrounding the cathodes, by varying the electrostatic field intensity or by varying the magnetic field intensity. Thus, modulation may be effected by varying the quantity of electrons flowing to the phosphor bodies. Similarly an increase in the potential applied between the cathodes and the anodes 12a will increase the number of electrons flowing through the phosphor sheets 10a and consequently increase the light output from the sheets 10b and 10c. However, such increase in potential will cause the angle of incidence which the electrons make with the plane of the sheets 10a to be somewhat greater, thereby reducing the efficiency of secondary electron liberation from the impinged phosphor sheet and resulting in a decrease in the total light output. Similarly an increase in the strength of the magnetic field for a given spacing between the cathode and sheets 10a will produce increased secondary electron emission from the impinged phosphor sheets but when the magnetic field is increased to such a value that the value of D in the above equations is less than the distance separating the cathode and sheets 10a, the electrons will fail to impinge on the phosphor sheets reducing the light output to a very low value or zero value. Electrons liberated by the cathodes 11 are liberated with a finite emission velocity which is added to the velocity produced by the potentials applied to the anodes, as a consequence the electrons impinging on the surface of the phosphor sheets with a relatively narrow range of velocity and for any given magnetic field will follow paths of different curvatures to the phosphor sheet. Consequently small variations in the strength of the magnetic field from the field strength at which the electrons are just grazing the phosphor sheet surface will produce large variations in light output of the device. In this manner the light output may be varied over very wide limits with relatively small variations in the magnetic field strength. For purposes of control I have shown a magnetic coil 15 as energized from a source of direct current potential 16. Modulating potentials may be applied in series with the potential source 16 which for modulating purposes is adjusted to a point at which the electrons from cathodes 11 are just grazing the surface of the phosphor sheets 10a, the modulating potential then being applied such as at 17 to control the light output of the device.

While I have described my invention with respect to a modification wherein the transparent phosphor bodies are in the form of sheets, my invention is susceptible of use wherein the bodies are of cylindrical form. Referring to Figures 3 and 4 the envelope 1 including the lens or transparent portion 2, reflecting portion 3, and coil 15 are similar to those shown in Figures 1 and 2. The phosphor bodies, however, are in the form of cylindrical phosphor members 20 two of which

are shown at 20a and 20b. In this modification a single cathode 21 may be provided coaxially of the members 20a and 20b with the anodes in the form of wire mesh screen, so as to be electron permeable, being interposed between the cathode 21 and member 20a as shown at 22a and between the member 20a and 20b, as shown at 22b. The cylindrical assembly comprising the cathode phosphor members and anodes may be supported by transparent cross shaped members 23 located at the opposite ends of the envelope. Obviously additional support members may be utilized between the ends of the structure if such are desired or necessary because of the length thereof. The spacing between the cathode and the member 20a and between 20a and 20b may be chosen in the same manner as described with reference to Figures 1 and 2. Likewise the potentials applied between the cathode and anodes are chosen to provide penetration of the electrons through the phosphor member 20a. Similarly additional cylinders of solid transparent phosphor material may be utilized as described in connection with Figures 1 and 2.

For the cylindrical phosphor body construction the above equations are modified in terms of the radius R, measured in centimeters, of the cylindrical phosphor body. From the above equations:

$$R = \left(\frac{8V}{H^2 e/m} \right)^{\frac{1}{2}} \quad (4)$$

which becomes

$$R = \left(\frac{6.72 V}{H^2} \right)^{\frac{1}{2}} \quad (5)$$

The same consideration with respect to spacing and modulation of the device of Figures 3 and 4 apply as given in connection with the operation of the device of Figures 1 and 2 and will not be repeated in detail.

While I have indicated the preferred embodiments of my invention of which I am now aware and have also indicated only several specific applications for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

I claim:

1. A luminescent device comprising an elongated envelope having a transparent end portion, a substantially optically transparent luminescent phosphor body extending longitudinally of said envelope, means oppositely disposed from and exposed to said body to develop a flow of electrons radially of said envelope, means to direct said electrons in a direction substantially normal to the surface of said body, and means to direct said electron flow along paths intersecting the longitudinal surface of said body at oblique angles to excite said body to luminescence and liberate secondary electrons from the surface of said body.

2. A luminescent device comprising an elongated envelope having a transparent end portion, a light reflective coating on the walls of said envelope with the exception of said end portion, a plurality of substantially optically transparent luminescent phosphor bodies extending longitudinally of said envelope, means to develop a flow of electrons radially of said envelope and in a direction substantially normal to the surface of said

bodies and means to direct said electron flow from said direction and along curved paths incident upon said bodies at oblique angles with respect to the longitudinal surfaces of said bodies thereby liberating secondary electrons from said bodies in excess of the electrons of said flow and exciting said bodies to intensive luminescence.

3. A luminescent device comprising an elongated envelope, means to develop a magnetic field having lines of force extending longitudinally of said envelope, a plurality of elongated phosphor bodies within said envelope, immersed in said field and positioned with their longitudinal surfaces substantially parallel to said field, and means to develop a flow of electrons moving transversely of said field and intercepting said bodies at oblique angles with respect to the surfaces thereof to liberate secondary electrons from said surfaces and to excite said bodies to luminescence.

4. A luminescent device comprising an envelope, a plurality of elongated optically transparent phosphor bodies within said envelope, said bodies being of sufficient length to exhibit total internal reflection along the length thereof, means to subject said bodies to an electron flow to develop light, means to intensify the light developed by said bodies comprising a magnetic field generating coil extending longitudinally of said bodies to direct said electron flow upon said bodies at oblique angles with respect to the surfaces of said bodies, and means associated with said magnetic field generating coil to vary the intensity of said light whereby said light may be modulated.

5. A luminescent device comprising an evacuated envelope, a source of electrons, a luminescent optically transparent phosphor body exposed to said source, an anode between said source and said phosphor body to direct electrons thereto, and magnetic field generating means surrounding said envelope and developing magnetic lines of force substantially parallel with the surface of said phosphor body to direct said electrons along curved paths intersecting said phosphor body at oblique angles with respect to the said exposed surface to develop light and liberate secondary electrons from said phosphor body.

6. A luminescent device comprising a source of electrons, a plurality of solid optically transparent phosphor bodies, at least one of said bodies being directly exposed to said source the remain-

ing bodies being at increasing distances from said one body and said source, and means comprising a plurality of anodes to direct electrons from said source through said bodies and upon the body most remote from said source thereby developing luminescence in each of said phosphor bodies.

7. A device as claimed in claim 6 including means to develop a magnetic field having lines of force extending substantially parallel with the surface of the transparent phosphor body exposed to said source to direct electrons along curved paths intercepting said bodies.

8. A luminescent device comprising an electron source to liberate electrons, a plurality of optically transparent phosphor bodies each of said bodies being spaced at progressively increasing distances from said source, said bodies having their minimum dimension in the direction of spacing from said source, an anode between the said source and the nearest adjacent phosphor body and an anode between each of the remaining phosphor bodies to accelerate electrons from said source, through said adjacent phosphor body and upon the body most remote from said source.

9. A luminescent device comprising a source of electrons, an electron permeable optically transparent phosphor body on opposite sides of said source an additional phosphor body positioned to receive electrons from said source passing through said first-mentioned phosphor body on opposite sides of said source, and an anode between said source and an anode between said bodies to direct electrons from said source through said first-mentioned phosphor body and upon said additional phosphor body.

10. A luminescent device comprising an electron source, a cylindrical transparent electron permeable phosphor body surrounding and coaxial with said source, means to direct electrons from said source through said body, phosphor means positioned to intercept electrons passing through said body and an anode between said body and said phosphor means to reaccelerate electrons passing through said body.

11. A device as claimed in claim 10 including a magnetic coil coaxial with said cylindrical phosphor body to direct the electrons from said source along curved paths intersecting said body and said phosphor means to liberate secondary electrons therefrom in excess of the number of electrons from said source impinging thereon.

HUMBOLDT W. LEVERENZ.
